SAFETY DEVICE FOR FOOT KICK PRESSES

Christian J. Schuhmann, Brooklyn, N. Y.

Application February 26, 1943, Serial No. 477,324

3 Claims. (Cl. 192—131)

This invention relates to new and useful improvements in foot kick presses, and has more particular reference to a safety device which makes it impossible for an operator's hand to be caught in the press.

More particularly, the invention proposes to characterize the safety device by a bolt which normally locks the head of the press from closing, and handles which must be gripped by the operator's hands and manipulated to release the bolt for allowing closing of the press.

The invention proposes a new construction in which one handle which must be gripped by one hand, and locks another handle which must be gripped by the other hand. The first referred to handle is first operated, releasing the second handle which is then operated to withdraw the bolt.

The invention also proposes an arrangement for immediately re-locking the head of the press when it reaches its raised position and when the operator releases the handles.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a foot kick press constructed in accordance with this invention.

Fig. 2 is a fragmentary enlarged elevational view looking in the direction of the line 2—2 of Fig. 1.

Fig. 3 is a plan view of Fig. 2 with certain parts broken away to disclose interior parts.

Fig. 4 is a fragmentary enlarged sectional view taken on the line 4—4 of Fig. 2.

Fig. 5 is a fragmentary enlarged sectional view taken on the line 5—5 of Fig. 3.

The safety device for foot kick presses, in accordance with this invention, is used in conjunction with a press 10 having the usual vertically slidable head 11, slidable in the frame 12 of the press and controlled with a foot kick lever 13. Further details of the press will not be given in this specification as it forms no part of this invention.

The safety device includes a bolt 14 slidably mounted forwards and rearwards of and on the frame 12 of the press. This bolt engages a keeper or keeper opening 15 on the slidable head 11 of the press for latching said head in its raised position. A handle 16 is provided connected with the

bolt 14 for retracting the bolt to free it from the head 11 which then may be moved downwards. A latch is provided for holding the handle 16 from being moved and this latch includes an operator handle 17 adapted to be gripped with the other hand and moved for releasing said handle 16.

The handle 16 is supported by a screw 18 or other support element which passes through an opening in the handle and which is mounted on a boss 19. This boss 19 has an inclined outer end 20 which limits pivoting of the handle 16 from the full line position shown in Fig. 3 to the dot and dash line position indicated by reference numeral 16'. The inner end of the handle 16 has an elongated opening 21 which engages over the outer end of the bolt 14. A pair of headed pins 22 are mounted upon the outer end of the bolt 14 and engage slots 23 formed in the sides of the handle 16. The bolt 14 is slidably mounted in a casing 24 which is attached on the front of the frame 12. The construction is such that the free end of the handle 16 may be pressed rearwards to pivot the handle so that its inner end moves outwards and this motion will pull the bolt 14 forwards, disengaging it from the head 11. A spring 25 is coaxially mounted on the bolt 14 and acts between the front wall of the casing 24 and a flange 26 mounted on the bolt 14. This spring 25 resiliently urges the bolt to its rear operative position.

The latch for holding the handle 16 includes said handle 17 which is swivelly mounted by a screw 28 or other fastening element. A spring 29 is connected between the handle 17 and the casing 24 and urges the handle 17 into its operative position against a pin 30 mounted on the front wall of the casing 24. In this operative position, the inner end of the handle 17 is engaged over the inner end of the handle 16 locking the latter from being moved. The handle 17 may be pivoted, as indicated by the dot and dash lines 17' in Fig. 2 so that its inner end is moved free from the inner end of the handle 16. The latter is then free to be operated.

The operation of the safety device is as follows:

As illustrated on the drawing, the head 11 of the press is in its locked position. The material to be cut or stamped out is engaged between the dies of the press. The operator cannot kick the lever 13 for operating the press because the head of the press is locked. The operator must now grip the handles 16 and 17. Then the handle 17 must be pivoted to the position indicated by the line 17'. This frees the handle 16 which

must then be pushed to the position indicated by the dot and dash line 16'. This withdraws the bolt 14, and the operator may now kick the lever 13 to operate the press. It should be noted that it is impossible for the operator to catch his hands in the press since they are busy holding the handles 16 and 17 and are no place near the dies of the press.

After the lever 16 has been kicked and released the operator releases the handles 16 and 17 to move the material being stamped. The spring 25 immediately moves the bolt 14 rearwards which catches into the key opening 15 of the press head 11 when the press head reaches its fully raised position. The spring 29 cannot return the lever 17 to its initial position because its inner end will rest against the end of the handle 16, until such time that the bolt 14 moves rearwards. Then the spring 29 will pivot the handle against the inner end of the handle 16 and the safety device is now in condition to operate again.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a foot-kick press having a slidable head working in a frame and controlled with a foot-kick lever, a bolt slidably mounted forwards and rearwards of and on said frame and engaging a keeper opening on said head for latching said head in its raised position, a handle adapted to be gripped with one hand and moved for retracting said bolt, and a latch for holding said handle from being moved and having an operator handle adapted to be gripped with the other hand and moved for releasing said first named handle, said first named handle

being supported by a supporting element on a member having an inclined face which limits hinging of the handle on its support, the inner end of said first named handle having an opening engaged over the front end of said bolt, and fastening elements mounted on the bolt and engaging slots in the inner end of said handle.

2. In combination with a foot-kick press having a slidable head working in a frame and controlled with a foot-kick lever, a bolt slidably mounted on said frame to move forwards and rearwards thereof and engaging a keeper opening on said head for latching said head in its raised position, a handle having one end attached to said keeper and pivotally mounted intermediate of its ends so that its attached end will move forwards and rearwards of said frame to withdraw said bolt, and a latch having one end engaged over the attached end of said handle preventing said handle from being pivoted forwards and being turnably mounted to move laterally off the attached end of said handle freeing it to be movable forwards.

3. In combination with a foot-kick press having a slidable head working in a frame and controlled with a foot-kick lever, a bolt slidably mounted on said frame to move forwards and rearwards thereof and engaging a keeper opening on said head for latching said head in its raised position, a handle having one end attached to said keeper and pivotally mounted intermediate of its ends so that its attached end will move forwards and rearwards of said frame to withdraw said bolt, and a latch having one end engaged over the attached end of said handle preventing said handle from being pivoted forwards and being turnably mounted to move laterally off the attached end of said handle freeing it to be movable forwards, said handle being pivotally mounted on a member having its front face inclined slightly laterally and rearwards limiting pivoting of said handle to a forward and rearward directions.

CHRISTIAN J. SCHUHMANN.
